UNITED STATES PATENT OFFICE.

ARTHUR P. PAINE, OF WORCESTER, AND HAROLD L. BLANCHARD, OF MILLBURY, MASSACHUSETTS, ASSIGNORS TO CROMPTON & KNOWLES LOOM WORKS, OF WORCESTER, MASSACHUSETTS, A CORPORATION OF MASSACHUSETTS.

WEFT-REPLENISHING DOUBLE-FABRIC LOOM.

Application filed November 10, 1927. Serial No. 232,421.

This invention relates to a loom in which a double fabric may be woven by the use of two shuttles, one of which travels in the lower shed and the other in the upper shed. Such 5 looms are commonly used in the simultaneous production of two pile fabrics, such as plush, velvets or certain kinds of carpet. A loom of this general type is shown in the prior patent to Shuttleworth, No. 354,358, issued 10 December 14, 1886.

It is the general object of our present invention to provide weft replenishing mechanism for such a loom, by which the weft in either the upper or the lower shuttle may be 15 automatically replenished upon indication of weft exhaustion therein.

A further object is to provide mechanism for indicating such weft exhaustion in either shuttle and for controlling the operation of 20 the weft replenishing mechanism. We have also provided improvements in the picking mechanism particularly applicable to the purposes of this invention.

Our invention further relates to arrangements and combinations of parts which will be hereinafter described and more particularly pointed out in the appended claims.

A preferred form of the invention is shown 30 in the drawings, in which Fig. 1 is a front elevation of our improved weft replenishing mechanism and portions of the loom to which it is applied;

Fig. 2 is a plan view of the mechanism shown in Fig. 1;

Fig. 3 is a detail end elevation, looking in the direction of the arrow 3 in Fig. 1;

Figs. 4 and 5 are sectional end elevations, taken along the lines 4-4 and 5-5 in Fig. 2, respectively;

Fig. 6 is a partial plan view, taken along the line 6-6 in Fig. 4;

Fig. 7 is a detail sectional end elevation of certain parts, taken along the line 7-7 in Fig. 6;

Fig. 8 is an end elevation of parts of the loom, showing the picking mechanism;

Fig. 9 is a front elevation of the picking mechanism shown in Fig. 8;

Fig. 9^a is a diagrammatic view, illustrating the type of fabric to be woven in our improved loom;

Fig. 10 is a partial plan view, showing weft

detecting mechanism adapted for use in our improved loom;

Fig. 11 is a diagrammatic sectional end 55 view, taken along the line 11-11 in Fig. 10;

Fig. 12 is a front elevation, partly in section, of the weft detecting mechanism, taken substantially along the line 12-12 in Fig. 10;

Fig. 13 is a plan view of parts of the mechanism for transmitting an indication to the weft replenishing mechanism;

Fig. 14 is a sectional end elevation, taken along the line 14-14 in Fig. 13;

Fig. 15 is a partial plan view indicating the 65 relative positions of the shuttles when boxed;

Fig. 16 is a sectional end elevation, taken along the line 16-16 in Fig. 15, and

Fig. 17 is a view similar to Fig. 16, but showing the parts in a different position.

Referring to Figs. 8 and 9, we have indicated a portion of a loom frame 20 having a lay 21 mounted upon a rock shaft 22 and connected by arms 23 to a crankshaft 24 by which it is swung forward and rearward in the usual 75 manner.

The shuttle S (Fig. 9^a) travels back and forth in the lower shed of a double pile fabric, between the lower warp threads W and the middle warp threads W', while a second shuttle S' travels in the opening between the middle warp threads W' and the upper warp threads W².

The lay 21 is provided with superposed 80 shuttle boxes 26 and 27 (Fig. 9). The shuttle box 26 underlies and supports the box 27 and extends to the right thereof as indicated in Fig. 9 and the top and bottom of each shuttle box are open, so that a bobbin may be freely inserted in either shuttle or ejected 90 therefrom by direct downward movement.

Separate pickers 28 and 29 (Fig. 8) are provided for the shuttles S and S' respectively, said pickers being mounted to slide on the usual spindle rods and being actuated by 95 separate picker sticks 30 and 31. The sticks 30 and 31 are separately pivoted on the rock shaft 22 of the lay and are provided with offset portions through which they are actuated by pick levers 32 and 33. These levers have 100 pick cam plates 34 positioned for engagement by rolls 35 and 36 on crank arms 37 and 38 secured to a bottom or cam shaft 39. The shaft 39 is commonly arranged to rotate once for

every two revolutions of the crankshaft 24. The cam roll 35 has an adjustable bolt and slot connection with its crank arm 37, so that the timing of the pick for the shuttle S may be varied relatively to the timing of the pick for the shuttle S'.

It is desirable that the upper shuttle be substantially superposed upon the lower shuttle when in flight, in order that it may be supported thereby during its travel across the lay. Consequently it is necessary that the two pick motions should be so timed that the shuttle S will begin its flight slightly before the shuttle S' in order that its may advance to a position under the shuttle S' as the latter shuttle begins its flight. In order to secure this exact timing, the adjustable bolt and slot connection of the roll 35 to the arm 37 is provided.

20 *Weft replenishing mechanism.*

Referring now to Figs. 1 and 2, we have provided a simple magazine M to replenish the shuttle S and a similar magazine M' for the shuttle S'. Each of these magazines comprises a head plate 40 and a supporting plate 41, secured in spaced relation by tie rods 42. The head plate 40 is provided with a groove or channel 44 (Fig. 6) to receive the butts of the bobbins and the supporting plate 41 is provided with a similar groove or channel to receive the tips of the bobbins.

These grooved channels are preferably substantially vertical in their upper portions and 35 segmentally curved rearwardly in their lower portions, as indicated in Fig. 5, so that a bobbin may be delivered thereby to a position for direct downward transfer to the shuttles S or S'.

40 A transerrer 50 (Fig. 2) is provided for the magazine M, said transerrer being pivoted on a stud 52 mounted in a bracket 53 secured to the breast beam 54 of the loom. A corresponding transerrer 60 is provided for the magazine M' mounted on a stud 62 on a bracket 63 also secured to the breast beam 54.

50 Coil springs 55 and 65 normally hold the transerrers in raised position and each transerrer is provided with a latch 56 or 66, mounted on a depending arm 57 or 67, connected with the corresponding transerrer. The latches 56 and 66 are positioned for engagement with lugs or daggers 58 and 68 on the lay 21, each latch being moved into the 55 path of its lug or dagger upon indication of transfer.

60 Suitable give-way springs 70 (Fig. 7) are provided for yieldingly retaining the lowermost bobbin in each magazine in position for transfer until engaged and forced downward by the corresponding transerrer. The latches 56 and 66 are positioned by bell cranks 59 and 69, which in turn are connected by links 72 and 73 to arms 74 and 75 mounted on upper and lower indicating rock shafts 76

and 77. The shafts 76 and 77 extend along the front of the loom to the opposite side of the loom where the weft detecting mechanism is located.

70 *Weft detecting mechanism.*

On the opposite side of the loom, two superposed shuttle boxes 80 are provided in which the shuttles S and S' may be received. These boxes 80 are directly over each other and they 75 are of the common type used in the ordinary double shuttle loom. Superposed weft detectors of any usual type are provided, the upper detector indicating the condition of the weft in the shuttle S' and the lower detector giving a corresponding indication for the shuttles.

80 For illustrative purposes, we have shown a common commercial form of side slip weft detector, each detector comprising a weft-engaging member 82 mounted to slide freely through a front swivel block 83 on a stand 84 and also slidable through a wide slot 85 in a rear support 86. A block 87 is mounted to slide transversely in the rear support 86 and 85 is provided with a notch 88 closely engaging the middle portion of the detecting member 82. A spring 89 surrounds the member 82 and is interposed between the swivel block 83 and the cross-piece 90 on the member 82, 95 thereby forcing the detecting member rearwardly until the cross piece 90 engages the rear support 86 and aligns itself therewith.

90 If the weft engaging member 82 encounters a bobbin having sufficient weft thereon, the 100 end of the member 82 engages the weft and is carried directly forward thereby, causing little side-wise motion of the notched block 87. If, however, the weft is substantially exhausted, the member 82 slides along the surface of the bobbin, thereby causing sliding movement of the block 87. The blocks 87 are connected by links 92 to indicating plungers 93. The plungers 93 are slidably mounted in supports 94 and 95 (Fig. 13) which are pivoted respectively on arms 96 and 97 which are 105 fixed to the indicating rock shafts 76 and 77 previously described. An actuator 100 is mounted to slide adjacent the ends of the indicating plungers 93 and is provided with 110 shoulders 101 and 102 for engagement with said plungers. The actuator 100 is regularly moved forward and rearward by a cam 103 (Fig. 14) acting through an actuating lever 104, a link 105 and a bell crank 106. 115

120 *Weft guiding device.*

125 Reference to Figs. 15 and 16 will indicate that a clear path must be provided underneath the shuttle S', so that an exhausted weft carrier B' may be ejected downwardly without engaging or breaking the weft F extending to the bobbin B in the shuttle S. As the weft F for the shuttle S would naturally extend directly underneath the shuttle S', as 130

- indicated in Fig. 15, we have provided a weft positioning member 110 having a lug or shoulder 111 at its rear end adapted to engage the filling F from the shuttle S as the lay 5 moves forward and to carry said weft F rearward as indicated in Fig. 17, so that it extends at the rear side of the opening through the shuttle S' and will not be engaged by a bobbin ejected therefrom.
- 10 We have also provided end holders 112 (Figs. 1, 2 and 3) each adjustable vertically and angularly in a block 113 which in turn may be adjusted angularly or axially on one of the spacing rods 42 of the magazine.

15

Operation.

Having described the details of construction of our improved loom, the operation thereof will be readily apparent. The 20 shuttles S and S' are picked simultaneously in the same direction across the lay and the shuttle S is picked slightly earlier from the magazine side than the shuttle S', so that it may advance and take a position under the 25 shuttle S' as the latter is picked, and so that it may provide a support for the upper shuttle throughout its flight.

The shuttles upon arriving at the opposite side of the loom are received in the boxes 80 and are engaged by the detecting members 82 of the upper and lower detecting mechanisms. If the weft in either shuttle is substantially exhausted, the corresponding member 82 slips sidewise, projecting the corresponding 35 plunger 93 into the path of a shoulder of the actuator 100, whereupon the plunger and its associated support 94 or 95 is pushed forward, rocking the corresponding shaft 76 or 77, and positioning the corresponding latch 40 66 or 56 in the path of the dagger 68 or 58. The associated transferrer is thereby depressed, transferring fresh bobbin to the exhausted shuttle.

It will be seen that the weft supply in either 45 shuttle may thus be replenished upon any alternate pick and that the replenishment of each shuttle is entirely independent of the replenishment of the other shuttle. Furthermore, it will be seen that the replenishment 50 takes place immediately upon the return of a shuttle to the magazine side and one pick only after the indication of weft exhaustion.

By the provision of very simple mechanism, we are thus able to automatically replenish 55 the weft supply in either shuttle of a double fabric loom, a result of great importance in the development of the textile art.

Having thus described our invention and the advantages thereof, we do not wish to be 60 limited to the details herein disclosed otherwise than as set forth in the claims, but what we claim is:—

1. In a weft replenishing loom, a lay having a pair of superposed shuttle boxes at one 65 end thereof, one of said boxes being at a

greater distance from the adjacent cloth selvage than the other box, shuttles for said boxes, and means to transfer a fresh weft carrier to a shuttle in either box by direct downward movement of the weft carrier. 70

2. In a weft replenishing loom, a lay having a pair of superposed shuttle boxes at one end thereof, one of said boxes being at a greater distance from the adjacent cloth selvage than the other box, shuttles for said 75 boxes, means to present both shuttles substantially simultaneously in both boxes at the replenishing side of the loom, and means to transfer a fresh weft carrier to a shuttle in either box by direct downward movement of 80 the weft carrier.

3. In a weft replenishing loom, a lay having a pair of superposed shuttle boxes at one end thereof, one of said boxes being at a greater distance from the adjacent cloth selvage than the other box, shuttles in said boxes, said boxes being located to position the shuttles therein out of vertical alignment with each other, and means to transfer a fresh weft carrier to either shuttle by direct downward 90 movement of the weft carrier. 95

4. In a fresh weft replenishing loom, a plurality of weft carrier magazines mounted on one side of the loom and at different distances from the adjacent selvage of the cloth, a lay having a plurality of shuttle boxes at the weft replenishing end thereof, shuttles for said boxes, and means to transfer a fresh weft carrier from either magazine to a shuttle on said lay. 100

5. In a loom, a lay having a pair of shuttle boxes fixed at different elevations at each end of the lay, said boxes being also substantially out of vertical alignment at the replenishing end of the lay, a separate shuttle for each two boxes, and means to replenish the weft in either shuttle by a substantially vertical transfer of a fresh weft carrier thereto. 105

6. In a weft replenishing loom, means to provide upper and lower warp sheds, a pair of shuttles operative simultaneously in said upper and lower sheds, means to give one of said shuttles a flight of predetermined length in one shed, means to give the other shuttle a flight of greater length in the other 110 shed, and means to insert a fresh weft carrier in either shuttle by direct downward movement, said replenishment in one shuttle taking place at a substantially greater distance from the adjacent cloth selvage than the replenishment in the other shuttle. 115

7. In a weft replenishing loom, means to provide upper and lower warp sheds, a pair of shuttles operative simultaneously in said upper and lower sheds, means to give one of said shuttles a flight of predetermined length in one shed, means to give the other shuttle a flight of greater length in the other shed, means to vary the relative timing of said flights and means to insert a fresh weft car- 120 125 130

- rier in either shuttle by direct downward movement, the shuttles being substantially out of alignment both vertically and horizontally when in transfer position.
5. 8. In a weft replenishing loom, means to provide upper and lower warp sheds, a pair of shuttles operative simultaneously in said upper and lower sheds, vertically aligned shuttle boxes therefor at one side of the loom, 10 shuttle boxes therefor superposed substantially out of vertical alignment at the other side of the loom, and means to insert a fresh weft carrier in either shuttle by direct downward movement when in said latter boxes.
15. 9. In a weft replenishing loom, means to provide upper and lower warp sheds, a pair of shuttles operative simultaneously in said upper and lower sheds, vertically aligned shuttle boxes therefor at one side of the loom, 20 shuttle boxes superposed substantially out of vertical alignment at the other side of the loom, a separate weft detecting mechanism for each shuttle at the first mentioned side of the loom, and separate means to insert a 25 fresh weft carriers in an indicated shuttle at the opposite side of the loom by direct downward movement of said weft carrier.
10. In a weft replenishing loom, means to provide upper and lower warp sheds, a pair 30 of shuttles operative simultaneously in said upper and lower sheds, means to insert a fresh weft carrier in either of said shuttles, and means to move the weft thread of said lower shuttle out of the path of a weft carrier ejected from said upper shuttle.
35. 11. In a weft replenishing loom, means to provide upper and lower warp sheds, a pair of shuttles operative simultaneously in said upper and lower sheds, means to insert a fresh 40 weft carrier in either of said shuttles, and means to move the weft threads of said lower shuttle rearwardly out of the path of a weft carrier ejected from said upper shuttle.
45. 12. In a weft replenishing loom, means to provide upper and lower warp sheds, a pair 50 of shuttles operative simultaneously in said upper and lower sheds, means to give one of said shuttles a flight of predetermined length in one shed, means to give the other shuttle a flight of greater length in the other shed, the boxes at one side of the loom being out of vertical alignment, means to transfer a weft carrier to a shuttle in either of said boxes by direct downward movement, and picking 55 mechanism adjustable to cause said shuttles to cross the lay in direct superposed relation.
13. In a weft replenishing loom, means to provide upper and lower warp sheds, a pair of shuttles operative in said upper and lower sheds, superposed boxes for said shuttles defining flights of different lengths, the boxes at 60 one side of the loom being out of vertical alignment, and separate weft carrier magazines for said latter boxes, disposed at correspondingly different elevations and at different distances from the adjacent cloth selvages.
14. In a weft replenishing loom, means to provide upper and lower warp sheds, a pair of shuttles operative in said upper and lower 70 sheds, superposed boxes for said shuttles spaced apart to define flights of different lengths, separate means to indicate weft exhaustion in each shuttle at one side of the loom, and separate means to insert a fresh 75 weft carrier in an indicated shuttle at the opposite side of the loom, said latter means operating at substantially different distances from the adjacent cloth selvages.
15. In a weft replenishing loom, means to 80 provide upper and lower warp sheds, a pair of shuttles operative in said upper and lower sheds, superposed boxes for said shuttles spaced apart to define flights of different lengths, separate means to indicate weft exhaustion in each shuttle at one side of the loom, and separate means to insert a fresh 85 weft carrier in an indicated shuttle at the opposite side of the loom on the next forward beat of the lay, said latter means operating at substantially different distances from the adjacent cloth selvages.
16. In a loom, a lay, a pair of shuttles, a shuttle box at one end of said lay, substantially twice the length of the associated 90 shuttle, a second and shorter shuttle box superposed on said first box and positioned over the portion of said first box near the adjacent selvage of the cloth, said box being both open from top to bottom to permit insertion 95 and ejecting of a weft carrier, and means to insert a fresh weft carrier in either shuttle.
17. In a weft replenishing loom, a lay having a plurality of superposed shuttle boxes at one end thereof, said boxes being substantially out of vertical alignment, shuttles for said boxes and means to replenish the weft in any one of said boxes by direct downward movement of the new weft supply.
- In testimony whereof we have hereunto affixed our signatures.

ARTHUR P. PAINE.
HAROLD L. BLANCHARD.
